LOCK LATCH

Milton H. Wells, Scarsdale, N. Y.

Application May 29, 1936, Serial No. 82,409

2 Claims. (Cl. 70—367)

My present invention relates to locks and more particularly to an improved lock latch.

While my invention is applicable to any situation in which a lock may be utilized, it is particularly applicable for use on structures composed of thin material as for example sheet metal, in which the sheet metal may have a considerable range of movement under pressure. Also, it is particularly applicable in connection with containers and wherein it is desired that the catch of the lock may have a movement independent of the movement which may be imparted to it by the key or other operating means of the lock. Such a construction is desirable where, when the cover of the container is opened and the lock is in locked position, it is possible to securely lock the cover in position by merely closing the same independently of using the key and which may be done by the provision of an independently movable catch.

A feature of my invention is an improved lock latch.

A feature of my invention is an improved combined lock and latch.

25 A feature of my invention is an improved combined lock and latch wherein the latch has a movement independent of the lock, and wherein the latch cooperates with a catch which permits a relative sliding movement without disturbing 30 the locking condition.

In the accompanying drawing:

Fig. 1 is a front elevation of a portion of a container to which my improved mechanism has been attached.

35 Fig. 2 is a sectional elevation on the line 2—2 of Fig. 1.

Fig. 3 is a rear elevation of the structure shown in Fig. 1, and

40 Fig. 4 is a sectional elevation on the line 4—4 of Fig. 2.

Referring to the drawing, 10 designates a portion of the body of a container, such as a box, in which the upper peripheral edge has been folded inward and upward as indicated by the 45 reference numeral 11 and inwardly as indicated by the reference numeral 12 to form a ledge, the folded portions 11 and 12 serve the useful purpose of stiffening the construction of the body 10 of the container and also furnishes a construction which when the cover 13 of the container 10 is in closed position and the depending skirt portion of such cover is in the position shown in Fig. 2, prevents unauthorized tampering with the locking mechanism within the container, the 50 depending skirt portion 14 of the cover 13 has

secured thereto the angle member 15 which contacts with the inwardly extending portion 12 of the container 10 and provides stop for limiting the downward movement of the cover 13 with respect to the container.

At any suitable point on the side of the container 10 is a perforation through which extends the barrel portion 16 of a cylinder lock. The barrel 16 is securely attached to the container 10 by a nut 18, a washer 19 being interposed between the nut 18 and the inner face of the container 10. Rotatably mounted within the barrel 16, as is usual, is a plug 20, and secured to, but rotatable on a reduced portion 25 of such plug 20 is a latch member 21 which is notched, 15 at 17, as clearly shown in the drawing, and the notched portion 17 engages with a catch 22 secured to the inner face of the cover 13 in any suitable manner, as by rivets 23.

The latch member 21 is operated by the usual 20 key adapted to be inserted in the slot 24 of the plug 20. Rotating the latch member 21 in a clockwise direction, as viewed in Fig. 1 releases the latch member 21 from the catch 22, and the cover 13 may be raised from the container 10. 25

It will frequently happen however, particularly where the container 10 is utilized, for example as a container for milk bottles, that the key for operating the plug 20 is not in the slot 24 and therefore the latch member 21 is in locked position and the cover 13 is open, and therefore the catch 22 is out of engagement with the latch member 21. Under such conditions with an ordinary lock it would be necessary for the milk man to be provided with a key in order to operate 30 the latch member 21 to such a position as to permit the catch 22 to be engaged by latch member 21 to enable him to safely place filled milk bottles in the container 10. To obviate this necessity, I have provided means in connection with 35 the latch member 21 and in its connection with the plug 20 which will permit the lock mechanism to remain in locked position and will permit a relative movement of the latch member 21 to allow the cover 13 to be moved to locked position. 40

The latch member 21 is, as stated above, mounted on but rotatable with respect to the plug 20. Such latch member 21 is held in position on a reduced portion 25 of the plug 20, and is held thereon by a washer 26 and screw 27. Extending 50 radially outward from the reduced portion 25 is a member 28 attached to or formed integral with plug 20 and which is housed within a slot 29, formed in the latch member 21. It is apparent therefore, that there will be a limited rotative 55

movement permitted the latch member 21 on the reduced portion 25 of the plug 20 within the limits of the slot 29, and this movement is sufficient to allow the end of the catch 22 to ride down on the bevel end of the latch member 21 and rotate the latch member in a counter-clockwise direction, as viewed in Fig. 3 and into the notch 17 formed in the latch member.

The plug 20, adjacent the reduced portion 25 is cut away, as indicated by the reference numeral 30 in Fig. 4. When the plug 20 is in the locked position the cut away portion 30 is in alignment with a recess 31 formed in the barrel 16. Resting within the recess 31 is one end of a coil spring 32, and the free end of this coil spring is adapted to be engaged by a pin 33, secured to the inner face of the cam 21.

With the latch member 21 and the plug 20 in the locked position, or in the position shown in Fig. 3 for example, the coil spring 32 rotates the latch member 21 in a clockwise direction, so as to have the notch 17 engage with the catch 22, and to bring one end of the slot 28 in the latch member 21 into engagement with the member 28 on the plug 20. If it is desired to open the container 10, the key (not shown) will be inserted in the slot 24, and the key utilized to rotate the plug 20 in a clockwise direction, as viewed in Fig. 1, or in a counter-clockwise direction, as viewed in Fig. 3, whereupon the member 28 engaging with one wall of the slot 29 will rotate the latch member 21, so as to free same from the catch 22, and the cover 13 may be raised. The key (not shown) may now be removed from the slot 24, and if it is desired to then close the cover 13, such cover is brought down and the catch 22 engaging with the bevel of the latch member 21, will rotate the said latch member 21 on the reduced end 25 of the plug 20 in a counter-clockwise direction, as viewed in Fig. 3, allowing the catch 22 to ride into registry with the notch 17 of the latch member 21, whereupon the spring 32, in its endeavor to regain its normal free position will rotate the plug 20 in a clockwise direction, as viewed in Fig. 3, so as to bring the latch member 21 into engagement with the catch 22.

To provide limiting stops for the plug 20 in its rotative movement, I provide a slot 35 in the barrel 16 and in which slot works a pin 36 secured to the latch member 21. The dimensions of the slot 35 correspond closely with the dimensions of the slot 29 in the latch member 21. The pin 36 in connection with the slot 35 provides a positive stop arrangement for limiting the rotative movement of the plug 20, and therefore the latch member 21, in either direction.

It is to be noted that the catch 22 extends down-

wardly, as shown in Fig. 2, and such catch 22 has relatively great length as compared with the thickness of the latch member 21. With this construction it is apparent that regardless of the flexibility of the material of which the container 10 is made that it will be practically impossible to move the latch member 21 out of locking engagement with the catch 22.

As a further precaution against unwarranted tampering with the locking mechanism, I extend the horizontal portion 12 of the upper edge of the container body 10 toward the catch 22, the clearance between the portion 12 and the catch 22 being only sufficient to permit the lower end of the catch 22 to clear the portion 12 when the cover 13 is being opened.

Whereas, I have described my invention by reference to specific forms thereof, it will be understood that many changes and modifications may be made without departing from the spirit of the invention.

I claim:

1. An improved cylinder lock comprising a casing, a plug rotatively mounted therein, means for limiting the rotative movement of the plug with respect to the casing, a latch member rotatively mounted on the plug, a stop member on the plug, a recess in the latch member housing the stop member and cooperating therewith to limit the rotative movement of the latch member with respect to the plug in either direction, a coil spring housed within the casing, a projection on the latch member engaging with one end of said coil spring whereby said coil spring is compressed upon rotative movement of the latch member in one direction and whereby said spring acts to rotate the latch member in the opposite direction.

2. An improved cylinder lock comprising a casing, an arcuate slot formed in said casing, a plug rotatively mounted in the casing, a pin secured to the plug and extended radially outward therefrom and housed within the arcuate slot, a latch member rotatively mounted on the plug, a stop member secured to the plug, a recess formed in the latch member and housing the stop member and cooperating with the stop member for limiting the rotative movement of the latch member in either direction, a resilient member cooperating with the latch member for resiliently rotating the same in one direction to bring the stop member into engagement with one end of the recess, said cooperating pin and arcuate slot in the plug and casing respectively forming a positive stop for positively limiting rotation of the plug with respect to the casing in either direction.

MILTON H. WELLS.
